[57] CLAIM

The ornamental design for a mobile cart for chain cutter, as shown and described.

DESCRIPTION

FIG. 1 is a perspective view of a mobile cart for chain cutter showing my new design;

FIG. 2 is a side elevational view thereof;

FIG. 3 is an opposite side elevational view thereof;

FIG. 4 is an end elevational view thereof;

FIG. 5 is an opposite end elevational view thereof;

FIG. 6 is a top plan view thereof;

FIG. 7 is a bottom plan view thereof;

FIG. 8 is a perspective view of a second embodiment of the design shown in FIG. 1;

FIG. 9 is a side elevational view thereof;

FIG. 10 is an opposite side elevational view thereof;

FIG. 11 is an end elevational view thereof;

FIG. 12 is an opposite end elevational view thereof;

FIG. 13 is a top plan view thereof; and,

FIG. 14 is a bottom plan view thereof.

Throughout the Figures, the lines drawn in phantom form no part of the claimed design.
